UNITED STATES PATENT OFFICE

RICHARD H. SCHWENDLER, OF CLEVELAND, OHIO, AND CARL W. MEHLING, OF KENMORE, NEW YORK, ASSIGNORS TO AMERICAN RADIATOR COMPANY, OF NEW YORK, N. Y., A CORPORATION OF NEW JERSEY

HEAD PROTECTOR

Application filed December 23, 1929. Serial No. 415,943.

Our invention relates to new and useful improvements in head protectors for use in sand blasting or like operations.

An object of our invention is to provide a head protector having means to prevent fracture of the medium which seals the sight opening.

Another object is to provide for the transparent medium a protecting screen which may be easily and quickly removed to permit cleaning of the transparent medium.

The invention consists in the improved construction and combination of parts, to be more fully described hereinafter, and the novelty of which will be particularly pointed out and distinctly claimed.

In the accompanying drawing to be taken as a part of this specification, we have fully and clearly illustrated a preferred embodiment of our invention, in which drawing—

Figure 1 is a view in front elevation of a helmet or head protector embodying our invention;

Fig. 2 is a view in front elevation, and partially in section, with the front screen member removed, and

Fig. 3 is a view in section on the line 3—3 of Fig. 1.

Referring to the drawing by characters of reference, 1 designates, generally, a head protector comprising a helmet proper 2 to the edge or brim of which is sealed a depending cape member 3, preferably of leather. In the front of the member 3 is a sight opening 4, which is preferably substantially rectangular, and the top edge of which is formed by the helmet brim. Overlying the member 3 along the periphery of opening 4 is a frame or plate member 5; preferably of metal, having at its top a rearwardly extending portion 6 which is inclined to the plane of the frame member and which lies upon and conforms to the helmet brim to which it is secured by rivets, or the like 7. The cape member 3 is sealed tightly to the member 5 by a substantially rectangular frame clamping member 8 having an inner marginal flange 9 which extends through opening 4 and is fixed along its edge to member 5, as at 10, by solder, or the like. Through the member 5 is a sub-

stantially rectangular opening 11 which registers with opening 4, and surrounding the opening 11 the member 5 has a recess which may be stamped out from the plane of the plate member providing a transverse flange portion 12 and a shoulder or seat portion 13. Closing and sealing the openings 4 and 11, is a transparent member or medium 14, preferably glass, which is positioned within the flange portion 12 and seats against the portion 13. The medium 14 is tightly secured in the recess by a rectangular frame 15 which may be journaled at its top on pins 16 seating in opposite apertures 17 in the portion 12. Gaskets 18 of rubber, or the like, are preferably provided to seal the joint between the medium 14 and member 5 and to resiliently cushion the frame 15. At the bottom of member 5 and bearing against member 8 is a locking member 19, preferably an eccentrically mounted disk, rotatable on a pin 20 passed through the members 5 and 8 such that the member 19 may be moved into overlying and clamping engagement with the bottom portion of frame 15.

On the outside of member 5 and on each side of opening 11, are vertically extending supporting angle members 21, which preferably extend above and below opening 11. One flange 22 of each member 21 is secured to member 5 by bolts 23 which are passed through the clamping member 8 and serve to clamp member 3 between members 5 and 8. The remaining flanges 24 of angle members 21 extend forwardly from member 5. Through flanges 24 above opening 11 are alined apertures 25, and through flanges 24 below opening 11 are alined apertures 26. Clamped between member 5 and flanges 22 is the vertical flange 27 of an angle member 28, the other flange 29 of which extends horizontally forward over and laterally beyond the flanges 24 to serve as a light shield. Overlapping and closely adjacent the flanges 24 and substantially parallel to the planes thereof, are vertical flanges 30 which are carried by and are preferably integral with a frame or plate member 31. The flanges 30 are of substantially the same length as flanges 24 and have alined apertures 32 at

the top thereof and alined apertures 33 at the bottom thereof, which register with apertures 25 and 26 respectively. Extending through apertures 25 and 32 is a hinge pin or member 34 which secures the flanges 24 and 30 together at their upper ends. Extending through apertures 26 and 33 is a pin or member 35 which secures the flanges 24 and 30 together at their bottom ends. The members 34 and 35 are provided at one end with extensions or loops 36, 37, respectively, which serve as hand grasps for removal and insertion of the members, and which also serve as stops to limit the inward movement on insertion of the pins or members into the apertures. On the front face of member 31 is a frame or plate member 38 which is secured to member 31 by bolts and nuts 38' or the like. Through members 31 and 38 is an opening 39 which registers and is substantially coextensive with opening 11. The opening 39 is closed by a screen member 40, preferably of fine wire mesh, which extends and is tightly clamped along its periphery between members 31 and 38. The plate member 38 extends laterally beyond and below the frame members 5 and 31 and above the angle member 28 and member 31 to protect them from injury or distortion by missiles. The front face of member 38 is covered by a resilient cushioning member 41, preferably of rubber, so that the blows of missiles impacting the same will be cushioned.

When the head protector is worn by an operator engaged in sand blasting, or like operations, the air is filled with dust which settles on the glass or transparent medium 14 obscuring the vision of the operator. When this occurs, access to the glass or medium 14 for cleaning is obtained by removing the pin 35 and swinging the screen member and its frame upward on the pin 34, the angle member 28 being of resilient metal which will bend to permit lifting of the screen member. If desired, the screen member and its supporting frame may be detached from the head protector by withdrawing both of the pins 34 and 35. It will thus be seen that the glass or medium 14 may be cleaned without the necessity of the operator removing the protector, or the transparent sight opening sealing medium 14.

What we claim and desire to secure by Letters Patent of the United States is:

1. A head protecting device comprising a head enclosing member having a sight opening, a transparent medium sealing said opening, said member having supporting means at the sides of and above and below said opening, a frame member having supporting means above and below said opening and co-operable with said first-named means to space said frame member from said enclosing member, said first-named and said second-named means having alined apertures above and be-

low said opening, horizontally positioned pins extending between and through said apertures to secure said members together, said frame member having an opening registering with said sight opening, and a screen member closing said second-named opening. 70

2. A head protecting device comprising a head enclosing member having a sight opening, a transparent medium closing said opening, substantially vertical flange members extending forwardly from said member at the sides of said opening, a frame member having rearwardly extending substantially vertical flange members cooperable with said first-named flange members, a hinge pin extending between said first-named flange members adjacent the upper ends thereof and through alined bearing apertures in said first and said second-named flange members to secure said frame member to said enclosing member and whereby said frame member can swing upward and outward on and from said first-named flange members, said frame member having an opening registering with said sight opening, and a screen member closing said second-named opening. 80

3. A head protecting device comprising a head enclosing member having a sight opening, a transparent medium closing said opening, substantially vertical flange members extending forwardly from said member at the sides of said opening, a frame member having rearwardly extending substantially vertical flange members cooperable with said first-named flange members, a hinge pin extending between said first-named flange members adjacent the upper ends thereof and through alined bearing apertures in said first and said second-named flange members to secure said frame member to said enclosing member and whereby said frame member can swing on said first-named flange members, said frame member having an opening registering with said sight opening, a screen member closing said second-named opening, and means to hold said screen member and said transparent medium in substantially parallel relation. 95

4. A head protecting device comprising a head enclosing member having a sight opening, a frame member surrounding said opening, a transparent medium secured to said frame member and closing said opening, vertical angle members secured to said frame member at the sides of said opening and extending above and below said opening and having forwardly extending flanges, front and rear plate members positioned in front of said frame members and having registering openings alined with said sight opening, a screen member closing said registering openings and positioned between said plate members, means clamping said plate members together and upon said screen member, said rear plate member having vertical rearwardly extending flanges overlapping said 105

first-named flanges, said forwardly and rearwardly extending flanges having alined top and bottom apertures, and pin members extending through said apertures to secure said 5 plate members to said frame member.

In testimony whereof we have hereunto signed our names.

CARL W. MEHLING.
